UNITED STATES PATENT OFFICE.

CLARENCE F. SCHULTZ, OF READING, PENNSYLVANIA, ASSIGNOR TO THE SCHULTZ UNDERWEAR COMPANY, OF READING, PENNSYLVANIA, A CORPORATION OF PENNSYLVANIA.

UNDERGARMENT.

1,073,782.

Specification of Letters Patent. Patented Sept. 23, 1913.

Application filed August 26, 1912. Serial No. 717,056.

To all whom it may concern:

Be it known that I, CLARENCE F. SCHULTZ, a citizen of the United States, residing at Reading, in the county of Berks and State of Pennsylvania, have invented certain new and useful Improvements in Undergarments, of which the following is a specification.

This invention relates to improvements in undergarments and it is particularly applicable to union suits made of tubular bodies. In making garments of this character, the diameter of the tubular member from which the garment is made, does, to a certain extent, limit the variation that may exist, with comfort, between the waist and hip measurement. In my present invention, I am able to secure, from a tubular member of uniform diameter, a suit having a relatively small waist diameter while the hip measurement is relatively larger.

The invention consists primarily in the particular manner of cutting the fabric.

The invention is more fully described in the following specification and clearly illustrated in the accompanying drawing, which shows in—

Figure 1, a blank tubular member from which the suit is to be cut. Fig. 2 shows the tube after the first operation. Fig. 3 is a rear view of the suit, as it will appear when folded along the central dotted line in Fig. 2. Fig. 4 is a rear view of the suit with the rear leg and seat portions in position.

The numeral 1 designates a tubular body, of uniform diameter from which the suit is to be cut. These members are placed in large numbers in a pile and cut to the form shown in Fig. 2. This shows the neck portion 3 and shoulder straps 4 cut out at the top, while at a point about midway of its length, or at the point decided upon for the waist line, the members are cut in a straight horizontal line in to the vertical center, indicated by numeral 5. From this central point, at the inner end of the line 5, the members are cut away at one side with a

sweeping or curved line 6, the curve or contour of which will determine the hip measurement in the finished garment.

50

When the bodies are cut as above described, they are opened and folded along the line $x-x$, assuming the shape illustrated in Fig. 3, which shows the upper or body portion made up of the tubular portion of 55 the member while the front leg portions will be considerably larger across the hip line, due to the curved cutting line 6. The rear leg and seat portions 7 of the garment are then attached to the garment by stitching 60 across the back and down the outside of each leg, as indicated by the heavy dotted lines 10.

It is evident that with this construction, the hip size may be increased very materially while the body portion is smaller, thus 65 overcoming undue strain on the seat and hip portions of the suit, preventing gaping, and insuring comfort.

I claim:—

A union garment comprising a tubular 70 body portion and an integral front depending portion, said depending portion increasing in width, throughout its length, from one-half of the entire circumference of the tubular body portion to a width greater than 75 one-half the circumference of the tubular body portion, said depending portion being slit throughout a portion of its length and being turned out from the body portion to form only the entire front halves of the legs 80 of the garment; and two sections seamed to the edges of the front halves of the legs and to the rear of the body portion across the entire width of said body portion, said sections forming the entire rear portions of the 85 leg portions and having overlapped free-edge portions forming a closure for the rear of the garment.

In testimony whereof I affix my signature in presence of two witnesses.

CLARENCE F. SCHULTZ.
